UNITED STATES PATENT OFFICE.

AUGUSTUS I. GALE, OF ALBION, MICHIGAN.

SULKY-PLOW.

SPECIFICATION forming part of Letters Patent No. 408,966, dated August 13, 1889.

Application filed February 21, 1889. Serial No. 300,649. (No model.)

To all whom it may concern:

Be it known that I, AUGUSTUS I. GALE, a citizen of the United States, residing at Albion, in the county of Calhoun and State of Michigan, have invented certain new and useful Improvements in Sulky-Plows, of which the following is a specification, reference being had therein to the accompanying drawings.

- 10 This invention relates to new and useful improvements in sulky-plows; and the invention consists in the peculiar manner in which the plow is adjustably supported in relation to the plow-beam, and, further, in the peculiar 15 provision made for controlling the caster-wheel which supports and guides the rear end of the plow-frame, all as more fully herein-after described, and shown in the accompanying drawings, in which—
- 20 Figure 1 is a perspective view of my improved sulky-plow, and Fig. 2 is a plan view thereof with the adjusting devices and levers omitted.

The supporting-frame of the plow is substantially of known construction, and consists of a triangular-shaped frame the base *a* of which is in the longitudinal direction of the plow, with the sides *b* and *c* secured thereto on the land side, and with the intermediate 30 bar *d* longitudinally secured between the bars *b* and *c*.

e is a crank-axle journaled in suitable bearings *f* and *g* and provided with the wheel *h*, which adjustably supports the frame on 35 the land side of the plow. The crank-axle is provided with a suitable hand-lever *i* and adjusting devices by means of which the crank-axle is turned up or down for the purpose of raising or lowering the frame, all as in the 40 well-known manner.

The plow-beam *j* is vertically adjustably secured in proximity to the base *a* of the plow-frame in the following manner: A slotted guide *k* is secured to the base *a* and engages the rear end of the plow-beam to guide it in its vertical adjustment, which latter is obtained in the usual manner by an adjusting-lever *l*, which is mounted upon the plow-frame in suitable proximity to the driver on 45 his seat, and provided with a connection *m* to the plow and with a notched segment *n*. The front end of the plow-beam passes loosely

through a slotted guide *o*, secured between the front end of the base *a* and side *c* of the frame. This guide is provided with the vertical guide-slots *p*, into which engages the fixed pin *q*, which is secured transversely through the plow-beam, and another adjusting-lever *r* is mounted upon the front portion of the frame in suitable relation to the driver and provided with a connection *s* with the plow-beam and with the notched segment *t*, as in the ordinary construction of such adjusting devices.

The draft is directly applied to the plow-beam by means of a suitable clevis *u*, secured to the front end of the plow-beam.

On the mold-board side the plow-frame is supported by the ground-wheel *v*, which is mounted upon a stub-axle which is secured to or formed integral with the vertical shaft *w*. This shaft is journaled in a suitable bearing *w'*, secured to the outside of the base *a* of the frame, and, projecting upwardly above the plow-frame, terminates in a lateral offset *w''*, to which the rear end of the guide-pole *x* is secured by a suitable coupling, all so arranged that by means of the construction described it keeps the wheel *v* in line with the draft of the plow.

The rear end of the plow-frame is provided with a vertical bearing *y*, which projects laterally on the outside of the plow-frame and in which is mounted the caster-wheel *z*, which supports and guides the rear end of the plow-frame. To the upper end of the pintle of this caster-wheel is secured the disk *A*, which is provided upon its upper face with a radial notch *B*. A similar disk *C* is secured near the upper end of the vertical shaft *w*, which carries the front wheel, and this disk upon its upper side is also provided with a notch *D*, the sides of which are provided with inclines *E*.

F is a rock-shaft longitudinally journaled in suitable bearings *G*, which are secured to the base *a* of the plow-frame, and this rock-shaft is provided upon its ends with the rock-arms *H* and *H'*, which are adapted to engage into the notches *B* and *D* of the disks *A* and *C*, respectively.

As long as the draft is applied in the direct line of the plow-beam, or nearly so, as in the action of plowing a straight furrow,

the draft holds the wheel v parallel, or nearly so, to the plow-beam, and in this position the rock-arm H' engages into the notch D , and simultaneously therewith the rock-arm H engages into the notch B , the caster-wheel being thereby locked in its position parallel to the plow-beam. As soon, however, as the plow is turned around to one side or the other at the end of the furrow the change in the direction 5 of the guide-pole z is imparted to the wheel v , and this turning of the wheel v lifts the rock-arm H' out of the notch D by means of one of the inclines E . This movement is communicated through the rock-shaft F to the rock-arm H , which thereby is also withdrawn 10 from its engagement with the notch, and thereby unlocks the caster-wheel to adjust itself to the turning movement.

As soon as the guide-pole resumes its normal alignment with the plow-beam after the turning is completed the rock-arm H' drops into the notch D and the rock-arm H into the notch B , thereby locking the caster-wheel again into its prescribed position for guiding 15 the plow-frame while cutting a straight furrow.

To prevent a slight deviation from a straight line in plowing, I enlarge the notch D sufficiently to give a limited free play to the rock-arm H' when engaged in said notch.

The weight of the rock-arms H and H' is sufficient to cause them to drop into the notches B and D by the action of gravity and remain in such position until forcibly displaced in turning, the notch B being sufficiently deep to form a positive lock against any accidental displacement of the rock-arm H .

What I claim as my invention is—

40 1. In a sulky-plow of the character described, the combination, with the plow-frame and the plow-beam supported thereon, of the front and rear guides provided therefor on the plow-frame, and in which the front and rear ends of said plow-beam are vertically and independently adjustable, and the vertical slots in the front guide into which lateral projections of the plow-beam engage, substantially as described.

50 2. In a sulky-plow of the character described, the combination, with the plow-frame and the plow-beam supported thereon, of the front and rear guides provided therefor on the plow-frame, and in which the front and rear ends of said plow-beam are vertically and independently adjustable, the vertical

slots in said front guide in which a transverse pin or equivalent lateral offset on the plow-beam engages, and a draft attachment applied to the front end of said plow-beam, 60 substantially as described.

3. In a sulky-plow of the character described, the combination of the parts a , b , and c of the plow-frame, the vertically-adjustable plow-beam j , the rear guide k of the 65 plow-beam, the front guide o of the plow-beam, provided with the slots p , the transverse pin q of the plow-beam engaging therein, and the adjusting devices applied to the front and rear ends of the plow-beam, 70 substantially as described.

4. In a sulky-plow of the character described, the combination, with the front guide-wheel controlled by the pole, of a rear supporting caster-wheel with the locking device 75 controlled by the front guide-wheel and consisting of the notched disks mounted on the vertical shafts or pintles of said wheels and the rock-shaft extending between and provided with the rock-arms resting loosely upon and 80 adapted to engage with the notches of said disks, substantially as described.

5. In a sulky-plow of the character described, the combination, with the front guide-wheel v , controlled by the guide-pole, of 85 the caster-wheel z , the disks A and C , secured to the vertical shafts or pintles on which the said wheels are adapted to turn, the notches B and D , formed, respectively in said disks, the inclines E on the notch D , and the rock-shaft 90 F , provided with the rock-arms H and H' , resting loosely upon and adapted to engage into these notches, substantially as and for the purpose described.

6. In a sulky-plow, the combination, with 95 the front guide-wheel controlled by the guide-pole, the caster-wheel, and the disks A and C on the shafts or pintles of said wheels, and formed upon their upper faces with notches, as shown, of the rock-shaft F , journaled in 100 bearings G and having its ends bent to form the rock-arms H H' , which rest loosely upon the tops of said disks and adapted to engage the notches therein, substantially as shown and described.

In testimony whereof I affix my signature, in presence of two witnesses, this 26th day of January, 1889.

AUGUSTUS I. GALE.
